UNITED STATES PATENT OFFICE

97,968

DESIGN FOR A BOTTLE OR SIMILAR CONTAINER

Alice Spalding Bowen, Honolulu, Territory of Hawaii, assignor to S. & G. Gump Co., Honolulu, Territory of Hawaii, a corporation of California

Application October 9, 1935, Serial No. 58,914

Term of patent 3½ years

To all whom it may concern:

Be it known that I, Alice Spalding Bowen, a citizen of the United States and a resident of Honolulu, T. H., have invented the new, original, and ornamental Design for a Bottle or Similar Container, of which the following is a specification, reference being had to the accompanying drawing, forming a part thereof.

Figure 1 is a perspective view of a bottle or similar container showing my new design, and

I claim:

The ornamental design for a bottle or similar container as shown.

ALICE SPALDING BOWEN.
